UNITED STATES PATENT OFFICE.

FRANK H. HANLEY, OF DETROIT, MICHIGAN.

ELECTRIC-IRON PLUG.

Application filed February 9, 1923. Serial No. 617,917.

To all whom it may concern:

Be it known that I, FRANK H. HANLEY, a citizen of the United States of America, residing at Detroit, in the county of Wayne and State of Michigan, have invented certain new and useful Improvements in Electric-Iron Plugs, of which the following is a specification, reference being had therein to the accompanying drawings.

10 In my companion application filed under even date there is disclosed an electric iron switch necessitating the use of a connector between the usual plug and the switch in order that the switch may be included in 15 one side of the electric circuit, and to obviate the necessity of using such a connector, I provide a special plug that may be substituted for the usual plug and thus permit of my switch being conveniently used in connection with an electric iron.

My improved plug is constructed so that it may be easily and quickly installed on the usual cord, conductor or flexible member by which an electric iron is connected to a 25 source of electrical energy, and the construction of the plug will be hereinafter described and then claimed.

Reference will now be had to the drawing, wherein—

30 Fig. 1 is a side elevation of an electric iron provided with my switch and a special plug;

Fig. 2 is a side elevation of one of the plug members or sections, and

35 Fig. 3 is a longitudinal sectional view of the plug.

In the drawing the reference numeral 1 denotes an electrically heated iron having a handle 2 with a push button switch 3 at the 40 forward end thereof, and at the rear end of said iron are posts 4 on which is mounted a detachable plug comprising members or sections 5 and 6 connected together by nut equipped screws 7. The plug members or 45 sections are made of insulation material and the confronting faces thereof provided

with recesses 8, 9 and 10. In the recesses 8 are sockets 11 and 12 to receive the posts 4 and the socket 11 has a leading out wire 13 extending through a side opening 14 in the plug member or section 6, said leading out wire extending to the push button switch 3.

Mounted in the recess 9 of the plug member or section 6 is a connector 15 provided with binding posts 16 and 17, the binding posts 16 having a leading out wire 18 extending through the opening 14 to the push button switch 3.

Mounted in the recesses 10 is the end of a flexible casing or conduit 19 containing a 50 cable 20 having leading in wires 21 and 22 with the wire 21 connected to the socket 12 and the wire 22 connected to the binding post 17 of the connector 15.

From the foregoing it will be observed 55 that the electrical connections enclosed by the plug permit of the push button switch 3 controlling the electrical operating circuit of the iron 1, and by furnishing the plug, switch and appurtenant parts an ordinary 60 electric iron may be equipped to permit of the user easily controlling the electric current to the iron.

A preferred form of plug has been shown and described but I would have it understood that the construction is susceptible to such changes as are permissible by the appended claim.

What I claim is:—

The combination with an electrical heating iron having posts, a switch, and a leading-in conductor, of a plug detachably mounted on said iron posts, sockets in said plug with one of said sockets connected direct to one of the leading-in wires of said 70 conductor, the other socket having a leading-out wire connected to said switch, and a connector in said plug establishing an electrical connection between said switch and the other leading-in wire of said conductor. 75

In testimony whereof I affix my signature.

FRANK H. HANLEY.
